UNITED STATES PATENT OFFICE

ERNST RICHARD MEINIG, OF WYOMISSING, PENNSYLVANIA

DESIGN FOR A STOCKING

Application filed May 16, 1929. Serial No. 31,256. Term of patent 14 years.

To all whom it may concern:

Be it known that I, ERNST RICHARD MEINIG, a citizen of the United States, residing at Wyomissing, in the county of Berks and State of Pennsylvania, have invented a new, original, and ornamental Design for Stockings, of which the following is a specification, reference being had to the accompanying drawing, forming part thereof.

The figure is a front perspective view of a stocking, showing my new design.

I claim:

The ornamental design for a stocking, as shown.

In testimony whereof I affix my signature.

ERNST RICHARD MEINIG.
